DESIGN FOR A LEATHER

Leonard I. Friedman, Brooklyn, N. Y.

Application July 6, 1936, Serial No. 63,678

Term of patent 3½ years

To all whom it may concern:

Be it known that I, Leonard I. Friedman, a citizen of the United States of America, residing in Borough of Brooklyn, county of Kings, city and State of New York, have invented a new, original, and ornamental Design for a Leather, of which the following is a specification, reference being had to the accompanying drawing, forming part thereof,

The figure is a plan view of a leather showing my new design.

A single unit of my design is substantially comprised within the area defined by the indicating lines shown on the drawing, which unit is repeated over the surface of the leather in the relation indicated.

I claim:

The ornamental design for a leather, substantially as shown and described.

LEONARD I. FRIEDMAN.
